CLAIM

The ornamental design for a LCD monitor, as shown and described.

DESCRIPTION

FIG. 1 is a top front perspective view of a LCD monitor showing our new design;

FIG. 2 is a front elevational view thereof;

FIG. 3 is a rear elevational view thereof;

FIG. 4 is a left side elevational view, the right side being symmetrical thereof;

FIG. 5 is a top plan view thereof; and,

FIG. 6 is a bottom plan view thereof.

1 Claim, 4 Drawing Sheets
